US0D1103917S

(12) **United States Design Patent** (10) Patent No.: **US D1,103,917 S**
(45) Date of Patent: ** Dec. 2, 2025

(54) **CHARGING BASE**

(71) Applicant: **Harman International Industries, Incorporated**, Northridge, CA (US)

(72) Inventors: **Oliver Thomas**, Shenzhen (CN); **Yanyang Jia**, Shenzhen (CN); **Matthew James Ward**, Shenzhen (CN); **Alexander Demin**, Munich (DE)

(73) Assignee: **Harman International Industries, Incorporated**, Northridge, CA (US)

(**) Term: **15 Years**

(21) Appl. No.: **29/908,706**

(22) Filed: **Jan. 15, 2024**

(51) LOC (15) Cl. **13-02**

(52) U.S. Cl.

USPC **D13/108**

(58) **Field of Classification Search**

(57) **CLAIM**

The ornamental design for a charging base as shown and described.

DESCRIPTION

FIG. 1 is a front perspective view of a charging base showing the new design;

FIG. 2 is a front view thereof;

FIG. 3 is a side view thereof;

FIG. 4 is an opposite side view thereof;

FIG. 5 is rear view thereof;

FIG. 6 is a top view thereof; and,

FIG. 7 is a bottom view thereof.

The broken lines in figures illustrate portions of the design that form no part of the claimed design.

1 Claim, 7 Drawing Sheets
